UNITED STATES PATENT OFFICE.

FRANK W. KNOWLES, OF SEATTLE, WASHINGTON.

BEET-HARVESTING MACHINE.

Application filed November 22, 1922. Serial No. 602,617.

To all whom it may concern:

Be it known that I, FRANK W. KNOWLES, a citizen of the United States, residing at Seattle, in the county of King and State of Washington, have invented certain new and useful Improvements in Beet-Harvesting Machines, of which the following is a specification.

The present invention relates to beet harvesting machines and has for its principal object to improve upon the topper disclosed in Letters Patent No. 1,401,413 issued to me on the 27th day of December, 1921.

The object of the invention is to produce a topper mechanism which will be simple and efficient in construction, reliable in operation, and well adapted for the purpose for which it is designed.

A particular object of the invention is to provide a practical structure which will operate without interference with the delivering mechanism such as is shown in said Letters Patent.

With the above and numerous other objects in view as will appear as the description progresses, the invention resides in certain novel features of construction, and the combination and arrangement of parts as will be hereinafter more fully described and claimed.

In the drawing—

Figure 1 is an elevation of the topper mechanism embodying my invention showing the same in conjunction with a raising or delivering mechanism similar to that disclosed in the aforementioned Letters Patent,

Figure 2 is a top plan of the topper mechanism,

Figure 3 is a fragmentary vertical section therethrough, and

Figure 4 is a detail view showing the roller cooperating with the cam track for operation of the grippers.

Referring to the drawing in detail it will be noted that the delivering mechanism partially illustrated here is substantially the same as that described in the aforementioned Letters Patent consisting of the hub portion 1 having radiating therefrom the grippers 2 which grasp the beets or rather the tops thereof and deliver the beets into the toppling mechanism about to be described.

The toppling mechanism disclosed in said Letters Patent has proved rather impracticable because when the fingers thereof are depressed they interfere and engage the

grippers 2 and it is the particular object of this invention to eliminate this inefficient operation of the structure described in said Letters Patent. My improved structure consists of the fingers 10 which are bowed intermediate their ends and have the diverging ends 11 through which the beets enter. The shanks 12 of these fingers extend parallel with each other. A platform 13 is provided at one end with a block or standard 14 through which these shanks 12 extend being loosely held in place by the members 15 which have inner rounded faces engaging with rounded recesses at each end of the apertures 16'. A bar 16 is provided at its ends with apertures for receiving the shanks 12 and is fixed in place by the collars 17. A vertical aperture is provided centrally in this bar 16 for receiving a bolt 18 about which is disposed a spring 19. The bolt 18 pierces the platform 13 and a nut 20 is disposed on each end thereof and thus it will be seen that the shanks 12 may pivot in vertical planes, the spring 19 through the intermediacy of the bar 16 holding them horizontally under normal conditions. A pair of standards 22 rise vertically from the platform 13 and are provided with arcuate shaped racks 23 which are engaged with pinions 24 keyed to the shanks 12 so that as these fingers pivot in vertical planes they will simultaneously rotate. As the beet passes through the curved ends 11 of the fingers 10, the top thereof being held by the grippers 2 as explained in the aforementioned Letters Patent the beet will have a tendency to depress or pivot downwardly the fingers 10. As these fingers move downwardly and the beet slides longitudinally thereof they will rotate and the bowed portions of the fingers will come towards each other always engaging the stock of the beet as it slides longitudinally thereof. Any portions of the fingers which are depressed to a plane lower than the edge of the grippers 2 would be rotated sufficiently so as to straddle them and not engage them.

A knife 25 is carried by a link 26. It is to be noted that the bracket 27 forming a part of the knife 25 is provided with an apertured lip having a corrugated face for cooperating with a corrugated lip extending from one end of the link 26 and a screw 28 holds these lips in engagement with each other so that there will be a rigid and adjustable relation between the knife and the

link 26. The link 26 is provided at its other end with an apertured lip having a corrugated face for cooperating with a lip 29 extending from the reciprocating head 30 and a screw 31 holds the link 26 in adjusted fixed relation to this lip 29. Thus the relation of the knife 25 may be readily adjusted as may be found desirable in relation to the reciprocating head 30. The reciprocating head 30 has its ends apertured for receiving the shanks 12 of the fingers 10 so as to slide longitudinally therealong. A connecting rod 33 is suitably attached to the head 30 and is operated by a crank 34 on the shaft 35 which may be rotated through a bevel gear 36. This bevel gear 36 is in mesh with a bevel gear 37 carried by a shaft 38 which is rotated by the gear 39 meshing with the valve gear 40 on the hub portion 1. The platform 13 is supported by suitable standards 41 preferably attached to the cam track 42 which is engaged by the rollers 43 on the grippers 2.

It is thought that the construction and operation of the device will now be readily understood when taken in conjunction with the structure shown in Letters Patent No. 1,401,413 and it should also be readily understood that the structure thus described may be utilized in conjunction with other delivering mechanisms and that numerous changes in the details of construction and in the combination and arrangement of parts may be resorted to without departing from the spirit of the invention as hereinafter claimed.

Having thus described my invention what I claim as new is:—

1. In a topper mechanism, a knife, a pair of fingers associated with the knife and bowed intermediate their ends, and means for rotating the fingers upon depression thereof in the manner and for the purpose specified.

2. In a topper mechanism of the class described, a knife, a pair of bowed fingers associated with the knife, shanks provided on the fingers, means for rotatably and pivotally attaching the ends of the shanks, and means for rotating the fingers upon depression thereof in the manner and for the purpose specified.

3. In combination, a knife, a pair of fingers associated with the knife and bowed intermediate their ends, means for supporting adjacent ends of the fingers so that they may be rotated and pivoted, standards provided with racks, and pinions on the fingers engaging said racks so that the fingers will be rotated when pivoted.

4. In a topper mechanism of the class described, a knife, a pair of fingers associated with the knife, said fingers being bowed intermediate their ends and provided with straight parallelly extending shanks, means for pivoting the shanks at their ends so that they may rotate, means for normally holding the shanks in a substantially horizontally position, and means for rotating the fingers upon depression thereof. 70

5. In a topper mechanism of the class described, a knife, a pair of fingers associated with the knife and provided with bowed intermediate portions and straight shanks disposed in parallelism, means for rotatably and pivotally mounting the ends of the shanks, means for normally holding the shanks in a substantially horizontal position, a pair of racks, and a pair of pinions one on each shank engageable with the racks so that the fingers will be rotated upon depression thereof in the manner and for the purpose specified. 75

6. In combination, a delivering mechanism and a topper mechanism associated therewith and including a knife, a pair of fingers associated with the knife so as to receive the beets from the delivering mechanism, said fingers being bowed intermediate their ends, means for pivotally and rotatably mounting the fingers, and means for rotating the fingers as the beets pass longitudinally therealong and depress the same whereby the fingers will properly guide the beets and clear the delivering mechanism in the manner and for the purpose specified. 80

7. In a beet harvesting machine, a topper mechanism including a pair of fingers having bowed portions and straight shanks, means for pivotally and rotatably supporting said shanks, means for normally holding the shanks in a predetermined plane, a reciprocating head movable along the shanks, means for reciprocating the head, and a knife disposed in proximity to the bowed portion of the fingers operated by said reciprocating head. 100

8. In a harvesting machine of the class described, a topper mechanism including a guide mechanism, and a reciprocating knife, means for reciprocating the knife including a head, and a link adjustably connected to the head and to the knife. 105

In testimony whereof I affix my signature in presence of two witnesses.

FRANK W. KNOWLES.
